Inventor:

John McCormick

UNITED STATES PATENT OFFICE.

JOHN McCORMICK, OF DES MOINES, IOWA.

DESIGN FOR A HAMMER AND STAPLE AND NAIL PULLER.

SPECIFICATION forming part of Design No. 30,445, dated March 28, 1899.

Application filed February 28, 1899. Serial No. 707,221. Term of patent 7 years.

To all whom it may concern:

Be it known that I, JOHN McCORMICK, a citizen of the United States, residing at Des Moines, in the county of Polk and State of

Iowa, have invented and produced a new and original Design for a Hammer and Staple and Nail Puller, of which the following is a specification, reference being had to the accompanying drawings, forming a part thereof, and

in which—

Figure 1 is a perspective view showing the exterior configuration of the different parts, and Fig. 2 is a sectional vertical central view.

The letter A designates the part designed for connecting a wooden handle therewith, and B is an integral round poll that extends at right angles from the handle portion and has a convex bottom face, as shown in Fig. 2.

C is an integral extension on the top of the

part A and has an inclined front face D. Its 20 side faces F are convex, and one of them has a transverse groove adapted to admit the heads of nails.

The top of the part C terminates in a contracted extension H, that is pointed and adapted to enter the top or closed end of a staple.

It is obvious the size and weight of the complete tool may vary as desired.

Having thus described my invention, what I therefore claim as new, and desire to secure 30 by Letters Patent therefor, is—

The design for a hammer, staple and nail puller, as herein shown and described.

JOHN McCORMICK.
